UNITED STATES PATENT OFFICE.

CHARLES C. STUTZ, OF PITTSBURG, PENNSYLVANIA, ASSIGNOR TO THE PITTSBURGH PLATE GLASS COMPANY, OF PITTSBURG, PENNSYLVANIA, A CORPORATION OF PENNSYLVANIA.

GRINDING GLASS.

SPECIFICATION forming part of Letters Patent No. 760,765, dated May 24, 1904.

Application filed November 20, 1903. Serial No. 181,921. (No model.)

To all whom it may concern:

Be it known that I, CHARLES C. STUTZ, a citizen of the United States, residing at Pittsburgh, in the county of Allegheny and State of Pennsylvania, have invented or discovered certain new and useful Improvements in Grinding Glass, of which improvement the following is a specification.

The invention described herein relates to 10 certain improvements in mechanism for rounding the edges of plates—such, for example, as sheets or plates of glass—and has for its object a construction and combination of parts or elements whereby the plate or grinder is 15 moved one relative to the other in directions at an angle to each other or in the arc of a circle concentric with the axis of the tool.

The invention is hereinafter more fully described and claimed.

20 In the accompanying drawings, forming a part of this specification, Figure 1 is a top plan view of my improved machine. Fig. 2 is a front elevation of the same. Fig. 3 is an end elevation of the machine on an enlarged scale. Fig. 4 is a detail view of the supporting-bed 25 and clamp. Fig. 5 is a detail view of the stopping and starting clutch mechanism, and Fig. 6 is a diagrammatic view illustrating the operation of the machine.

30 In the practice of my invention the tool—*e. g.*, grinder 1—is mounted in suitable bearings on the standards or pedestals 2, which are connected at their lower ends by suitable channel-bars 3, properly braced and forming 35 the bed of the machine. The tool or grinder is rotated by means of a belt passing around the pulley 4, and a reciprocating movement is imparted to the grinder by means of an eccentric 5 on a shaft 6, the strap of such eccentric being connected to a collar 7, arranged 40 between shoulders 8 on the grinder-shaft. The shaft 6 is driven by the belt passing around the pulley 9 through a worm-and-gear connection. A second gear connection extends 45 from the shaft of the pulley 9 to operate the gear-wheel 12 on the counter-shaft 13. Crank-arms 14 are secured on the ends of the coun-

ter-shaft and are connected by links 15 to one end of rocking levers 16, which have their axis in line with the axis of the tool and to 50 this end may be loosely mounted on the shaft of the grinder. As clearly shown in Fig. 3, levers 16 are provided at one end with guides for the movable blocks 17. It is preferred to form these guides by slotting the levers in 55 the manner shown. Provision is made for the adjustment of the blocks along the guides by means of the screws 17^a passing through the end walls of the slots and engaging the sliding blocks. Clamping-arms 18 and 19 are 60 pivotally connected to the sliding blocks 17, preferably by means of pins 20 passing through the ends of the clamping-arms and into the slides 17. One member of each pair of arms 19 has a pivotal connection to the 65 supporting-bed 21, and the other member of each pair has a similar connection to the clamping-bar 22. The connection of these parts with the arms is formed by pintles 23, projecting from the ends of the bed and clamping-bar and into suitable openings in the clamping-arms. Provision is made for shifting the outer ends of the arms so as to move the bed and clamping-bar toward and from 70 each other by screws 24, passing through blocks 25, pivotally mounted on the ends of the clamping-arms, as clearly shown in Figs. 2 and 3. The clamping-bed consists of end rails 26, connected by angle-bars 27, which are braced intermediate of the rails by suitable 75 cross-bars, as shown in Fig. 1. It is preferred to form the upper face of the supporting-bed by wooden slats, which will form an elastic or yielding cushion for the plates laid thereon. The clamping-bar 22 is formed by 80 an angle-bar which has short wooden bars or slats secured to the under face. The rails of the supporting-bed rest upon rollers 28, mounted on brackets extending from the bed of the machine, so that the supporting-bed can 85 be moved back and forth, as hereinafter described.

In operating the machine a plate of glass or other material is placed upon the support-

ing-bed with the edge to be ground projecting beyond the inner line of this bed. The screws 24 are then operated to first shift the clamping-bar 22 down upon the glass or plate, and 5 as soon as a firm bearing of the clamping-bar on the plate is effected the continued rotation of the screw will move both the bed and the clamping-bar toward each other, so that the clamping action will be uniformly toward 10 the surface of the plate. If the supporting-bed when the plate is clamped thereon, as in the position shown in Fig. 3—*i. e.*, with its upper surface in or approximately in a horizontal plane passing through the axis of the 15 grinding-roller—and the machine is constructed so that the crank-arms 14 are rotated in the direction of the arrow in Fig. 3, the table and plate will be moved downwardly by the levers 16 and also inwardly under the grinding-roller, 20 as shown in full lines in Fig. 6, whereby the upper corner of the plate is rounded. As the crank-arms continue to rotate past the position shown by the full lines in Fig. 6 the supporting-table, with the plate, will be moved 25 upwardly and outwardly until it again reaches the position shown in Fig. 3, thereby giving a smoothing cut to the previously-rounded portion. As the arms 14 continue to rotate the table will be raised and moved forwardly 30 over the grinding-stone to the position shown by the dotted lines in Fig. 6 and back again along the same path until it reaches the position shown in Fig. 3, whereby the lower corner of the plate is cut away and curvature 35 given to the plate. It will be observed that although the edge of the glass has traversed a convex surface coincident with the arc of a circle concentric with the axis of the grinder the movement has been such that this convex surface—*i. e.*, the periphery of the grinding-stone—will produce a convex surface on the edge of the plate operated upon, and, further, it will be observed that the edge of the glass is caused to move twice over the 40 same grinding-surface, a rough grinding being effected during the first movement and a smoothing action being effected on its next movement. As it is only necessary to have one revolution of the crank-arms to effect this 45 double grinding, provision is made for stopping the machine after each revolution of the crank-arms. To this end the gear-wheel 12 is loosely mounted upon the counter-shaft 13 and is provided with one member of a 50 clutch, the other member 29 being keyed to the shaft 13, so as to permit of its movement along the shaft, but to cause the shaft to rotate therewith. This clutch is moved back and forth by means of a lever 30, connected 55 by a rod 31 to a treadle 32. A spring 33 is so arranged as to normally tend to throw the movable member of the clutch out of engagement with the member on the gearing-wheel 12. After the glass has been clamped upon the 60 bed in the manner described the operator 65

pushes down the treadle, thereby throwing the member 29 of the clutch into engagement with the other member and compressing the spring. On the first movement of the member 29 of the clutch and the shaft 13 a collar 7c 34 on the member 29 is shifted so as to bring a slot or notch 35 therein out of alignment with an arm 36 on the bed of the machine, so that thereafter this arm will hold the members of the clutch in engagement and allow the operator to remove his foot from the treadle. As the clutch and shaft complete their revolution the notch in the collar 34 will come into alignment with the arm 36, whereupon the clutch member 29 will be shifted by the 80 spring out of engagement with the member on the gear-wheel. This collar is adjustably mounted on the clutch member 29, so as to permit of the stopping and starting of the machine in any desired position of the bed 26. 85 It will be understood that if it is necessary or desired to cause the plate to traverse the tool three or more times the operator will hold the treadle down and prevent disengagement of the members of the clutch. 90

By adjusting the slides 17 on the levers 16 the curvature to be given to the edge of the glass can be varied, the curvature being increased by shifting the slides outwardly.

I claim herein as my invention—

1. In a machine for rounding the edges of plates, the combination of a plate-holder, a tool and means for moving one of the said parts or members around a portion of the other in the arc of a circle concentric with the axis of the tool, substantially as set forth, 95

2. In a machine for rounding the edges of plates, the combination of a plate-holder, a tool, means for moving one of said parts or members around the other in the arc of a circle concentric with the axis of the tool, and means for automatically stopping such movement, substantially as set forth. 105

3. In a machine for rounding the edges of plates, the combination of a plate-holder, a rotating tool and means for moving the plate-holder in the arc of a circle concentric with the axis of the tool, substantially as set forth, 110

4. In a machine for rounding the edges of plates, the combination of a rotating tool, levers having their axes in line with the axis of the tool, a plate-holder having one end, or edge connected to the levers, supports for the opposite edge or end and means for rocking said levers, substantially as set forth. 115

5. In a machine for rounding the edges of plates, the combination of supporting-rollers, a plate-holder carried by said rollers, a rotating tool, levers having their axes in line with the axis of the tool, and pivotally connected 125 to the plate-holder, and means for oscillating the levers, substantially as set forth.

6. In a machine for rounding the edges of plates, the combination of a rotating tool, levers having their axes in line with the axis 130

of the tool, a plate-holder having pivotal connections with the levers, means for adjusting such connections and means for oscillating the levers, substantially as set forth.

- 5 7. In a machine for rounding the edges of plates, the combination of a rotating tool, levers having their axes in line with the axis of the tool, two pairs of clamping-arms pivotally connected to the levers, a plate-supporting bed pivotally connected to one member of each pair of clamping-arms, a clamping-bar pivotally connected to the other member of each pair of arms and means for oscillating the levers, substantially as set forth.
- 10 8. In a machine for rounding the edges of

plates, the combination of a rotating tool, levers having their axes in line with the axis of the tool, a plate-holder pivotally connected to the levers, a shaft provided with cranks connected to said levers, means for rotating the shaft and means automatically operative to arrest the rotation of the shaft, substantially as set forth.

In testimony whereof I have hereunto set my hand.

CHARLES C. STUTZ.
